UNITED STATES PATENT OFFICE.

ALFRED Z. BAKER, OF NEW YORK, N. Y.

DESIGN FOR A DOLL-PATTERN.

No. 39,979.

Specification for Design.

Patented May 4, 1909.

Application filed March 10, 1909. Serial No. 482,625. Term of patent 3½ years.

To all whom it may concern:

Be it known that I, ALFRED Z. BAKER, a citizen of the United States, residing in the borough of Manhattan, city, county, and State of New York, have invented a new, original, and ornamental Design for a Doll-Pattern, of which the following is a specification.

The nature of my design is fully represented in the accompanying drawing, to

which reference is made and which is a front elevation embodying my design.

I claim,

The ornamental design for a doll pattern, as shown.

ALFRED Z. BAKER.
